UNITED STATES PATENT OFFICE.

SOLOMON SHAPIRO, OF NEW YORK, N. Y., ASSIGNOR TO RELIANCE METAL SPINNING COMPANY, OF NEW YORK, N. Y., A COPARTNERSHIP COMPOSED OF SAMUEL SHAPIRO, JOSEPH SHAPIRO, SOLOMON SHAPIRO, DAVE SHAPIRO, AND MORRIS BERMAN.

DESIGN FOR AN OVAL BACK FOR BRACKETS FOR LIGHTING-FIXTURES.

48,796.

Specification for Design.

Patented Mar. 28, 1916.

Application filed November 20, 1915. Serial No. 62,646. Term of patent 3½ years.

To all whom it may concern:

Be it known that I, SOLOMON SHAPIRO, a subject of the Czar of Russia, residing in the city of New York, borough of Brooklyn, in the county of Kings and State of New York, have invented a new, original, and ornamental Design for an Oval Back for Brackets for Lighting-Fixtures, of which the following is a specification, reference being had to the accompanying drawing, forming part thereof.

Figure 1 is a side view of an oval back for brackets for lighting fixtures, showing my new design. Fig. 2 is a bottom plan view of the oval back shown in Fig. 1.

I claim:

The ornamental design for an oval back for brackets for lighting fixtures, as shown.
SOLOMON SHAPIRO.
